(57) **CLAIM**

The ornamental design for a foldable knife, as shown and described.

DESCRIPTION

FIG. 1 is a front perspective view of a foldable knife, showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the foldable knife of FIG. 1 with the knife blade retracted; and,

FIG. 9 is a back perspective view of the foldable knife of FIG. 1 with the knife blade retracted.

The broken lines depict portions of the foldable knife in which the design is embodied that are not considered part of the claimed design.

1 Claim, 4 Drawing Sheets
